UNITED STATES PATENT OFFICE.

SVEN GUSTAF WINGQUIST, OF GOTTFENBORG, SWEDEN, ASSIGNOR TO AKTIEBOLAGET SVENSKA KULLAGERFABRIKEN, OF GOTTFENBORG, SWEDEN, A CORPORATION OF SWEDEN.

BALL-BEARING.

1,168,693.

Specification of Letters Patent. Patented Jan. 18, 1916.

Original application filed April 27, 1912, Serial No. 693,735. Divided and this application filed February 26, 1913. Serial No. 750,876.

To all whom it may concern:

Be it known that I, SVEN GUSTAF WINGQUIST, a subject of the King of Sweden, residing at Gottenborg, Sweden, have invented certain new and useful Improvements in Ball-Bearings, of which the following is a specification.

The present application is a division of my application No. 693,735, filed April 27, 10 1912.

The principal object of the invention is to provide a sheet metal retainer for ball bearings, so arranged that it is of light weight, can be manufactured easily and sold 15 cheaply, and the balls can be readily located within and withdrawn from the same.

Other objects of the invention will hereinafter appear.

One feature of the invention consists in 20 the ring being curved or shaped as a cup opposite to and substantially inclosing each ball.

The invention further comprises other 25 constructions and combinations of parts which are described hereinafter.

The accompanying drawings show a plurality of forms of the retainer.

Figures 1 and 2 are respectively a diametrical section and an edge view of one 30 style of retainer embodying the invention; Figs. 3, 4 and 5 are respectively a diagrammatic face view, a diametrical section, and an edge view, showing another style of retainer embodying the invention.

35 The retainer consists of a ring 1 of sheet metal, which is located at one side of the set of balls 2, and is curved in cross-section in accordance with the curvature of the balls. The ring is so shaped that it forms 40 a cup at each ball, conforming to and engaging the balls at all sides except the sides in contact with the races, and substantially or approximately inclosing the same. For example, as illustrated, the outer 45 and inner portions of the ball (along a radial line of the bearing) are free to be engaged by the ball races; and the retainer engages the balls at the front and rear and also at the sides. In this construction the 50 cup shape is carried to such a degree that the bottom of the cup, viewed from the edge

of the ring, in the direction of the radius of the ring, forms substantially a semicircle or more than a semicircle. The cup is indicated by the numeral 6. The lips are 55 extended axially in a suitable curve, and both lips preferably uniformly and to such a degree that the edges practically or nearly meet.

The lips may be bent transversely, that is in a direction transverse to the axis of the bearing, independently of a greater or less depth of the cup 6, so that the flat face of the sheet metal forming the lips engages the side of the balls which the lips fit more 65 or less closely. This arrangement is shown in two slightly different forms, first in Figs. 1 and 2, and second in Figs. 3, 4 and 5; the lips being designated by the numeral 7.

Various other modifications may be made 70 on the same principle, namely,—that one edge or both edges of the ring or the ring itself, is bent inward into the spaces between the balls in such a way as to form a circle or a large part of a circle around the 75 imaginary circular line which passes through the center points of the balls; the edges of the retaining ring thus bent inward serving to keep the balls at their proper distances apart, without the necessity of 80 using thick material for the ring. In fact the ring is preferably made of thin material so that its parts which are bent inward are sufficiently yielding to permit the ready insertion and withdrawal of the balls into 85 and from the ring.

I claim as my invention:—

1. A ball retainer formed of sheet metal and comprising a ring formed as a series of cups for engaging the balls, the ring having 90 lips at its respective edges curved into the spaces between the balls and bent transversely, the flat face of the sheet metal forming the inner faces of the lips, the lips being curved so that said faces conform 95 more or less closely to, and engage the sides of, the balls.

2. A ball retainer formed of sheet metal and comprising a ring formed as a series of cups for inclosing the balls, the ring having 100 lips at its respective edges curved into the spaces between the balls and bent trans-

versely, the edges of the lips practically meeting, the flat face of the sheet metal forming the inner faces of the lips and conforming more or less closely to, and engaging the sides of, the balls.

In witness whereof, I have hereunto

signed my name in the presence of two subscribing witnesses.

SVEN GUSTAF WINGQUIST.
